ART OF CRACKING HYDROCARBONS

Willis S. Gullette, Highland, Ind., assignor to
 Sinclair Refining Company, New York, N. Y., a
 corporation of Maine

Application December 16, 1929, Serial No. 414,382

3 Claims. (Cl. 196—61)

This invention relates to improvements in the cracking of heavier and higher boiling hydrocarbon oils for the production of lighter and lower boiling hydrocarbon oils in operations in which the heavier or higher boiling oil is heated to a high cracking temperature while in the vapor phase.

The invention is of special value and application in conjunction with operations of the type described in an application filed June 13, 1927, Serial No. 198,621, by Harry L. Pelzer, but the invention is also useful in broader application.

This invention provides particularly improvements in operation which make possible the maintenance of continuously uniform cracking conditions while subjecting raw stock, or different raw stocks, and stocks produced in the operation, heavier or higher boiling than the desired product but freed from tar produced in the operation, to cracking conditions particularly advantageous with respect to the particular stock.

The complete combined operation of the present invention comprises three general steps; the invention also includes in combination the first and second steps, in combination the second and third steps, and in one aspect the third step itself, as separate operations.

In carrying out the first two steps of the improved operation of this invention, a stream of raw stock is heated to a high cracking temperature in the vapor phase in a heating conduit, the hot oil products discharged from this heating conduit are subjected to a scrubbing operation for the separation of tar and separated tar is discharge from this scrubbing operation, the vapors escaping from the scrubbing operation are subjected to a fractionating operation in which a condensate formed of constituents higher boiling than suitable as components of the desired product is condensed, none of this condensate is returned to the first mentioned heating conduit but a stream of this condensate is separately heated to a higher cracking temperature in the vapor phase in a separate heating conduit, the hot oil products discharged from this separate heating conduit are subjected to another scrubbing operation for the separation of tar and separated tar is discharged from this scrubbing operation, the vapors escaping from this scrubbing operation are subjected to another fractionating operation in which another condensate formed of constituents higher boiling than suitable as components of the desired product is condensed, none of this condensate is returned to either the first mentioned or the second men-

tioned heating conduit, and the desired product is condensed from the vapors escaping from the mentioned fractionating operations. In these two steps of the improved operation of the invention, none of the constituents condensed from the hot oil products discharged from either heating operation is returned, or "refluxed", to the heating operation in which such constituents are produced, but the more refractory higher boiling constituents condensed from the hot oil products discharged from the first heating operation, after separation of tar, are further cracked in the second heating operation in which such constituents are subjected to a higher cracking temperature.

In carrying out the third step of the improved operation of this invention, a stream of stock, condensate from the fractionating operation in the second step just described for example, is heated to a still higher cracking temperature in the vapor phase in another separate heating conduit, the hot oil products discharged from this heating conduit are subjected to another scrubbing operation for the separation of tar and separated tar is discharged from this scrubbing operation, the vapors escaping from this scrubbing operation are subjected to another fractionating operation in which another condensate formed of constituents higher boiling than suitable as components of the desired produce is condensed, and the desired product is condensed from the vapors escaping from this fractionating operation. In no case is all of the condensate separated in this last mentioned fractionating operation returned, or "refluxed", to the last mentioned heating operation, or either of the previously mentioned heating operations; at least a part of all constituents condensed from the hot oil products discharged from the third heating operation, after separation of tar, is discharged and not returned to any of the heating operations. Advantageously, in accordance with this invention, the condensate separated in the last mentioned fractionating operation is divided into two parts, of the same composition or of a common range of constituents, one part is returned to the third heating operation, and none of the other part is returned to the third heating operation, or either of the first two heating operations, thereby avoiding accumulation of any high boiling refractory constituent within the operation.

This invention will be further described in connection with the accompanying drawing which illustrates, diagrammatically and conventional-

ly, in elevation and partly in section and with parts broken away, one form of apparatus adapted for carrying out the process of the invention.

The apparatus illustrated comprises three heating conduits, 1a, 1b and 1c, arranged in heating furnaces 2a, 2b and 2c, three scrubbing towers, 3a, 3b and 3c, and three fractionating towers 4a, 4b and 4c. Raw oil is supplied to the heating conduit 1a through connection 5, by means of pump 6, and the hot oil products from the heating conduit 1a are discharged into scrubbing tower 3a through connection 7a. Oil is supplied to the heating conduits 1b and 1c through connections 8 and 9 respectively, by means of pumps 10 and 11 respectively, and the hot oil products from the heating conduits 1b and 1c are discharged into the scrubbing towers 3b and 3c respectively through connections 7b and 7c respectively. Tar separated in the scrubbing towers 3a, 3b and 3c is discharged therefrom through connections 12a, 12b and 12c respectively without returning this tar or any part of this tar, as such, to any of the heating conduits. The vapors escaping from each of the scrubbing towers 3a, 3b and 3c pass through connections 13a, 13b and 13c respectively to the fractionating towers 4a, 4b and 4c respectively, in which constituents heavier or higher boiling than suitable as components of the desired product, freed from tar and suitable for further cracking under appropriate conditions, are condensed. The vapors escaping from each of the fractionating towers 4a, 4b and 4c pass through connections 14a, 14b and 14c respectively to suitable condensing apparatus for recovery of the desired product, either directly or through suitable treating or fractionating apparatus. The condensate separated in fractionating tower 4a is supplied to pump 10, by which it is forced through heating conduit 1b, through connection 15, and the condensate separated in fractionating tower 4b is supplied to the pump 11, by which it is forced through the heating conduit 1c, through connection 16. The condensate separated in the fractionating tower 4c is either all discharged through connections 17, 18 and 19, valve 20 being closed, or in part discharged through connection 19 and in part forced, by means of pump 21, through the heating conduit 1c together with the condensate separated in the fractionating tower 4b, valves 20 and 22 being appropriately regulated. Raw oil may also be supplied to the heating conduits 1b and 1c through connections 23 and 24 respectively. Raw oil supplied to the heating conduit 1a may be used as a cooling medium, and thus preheated, in the reflux condensers for effecting or controlling condensation in the several fractionating towers 4a, 4b and 4c, as shown.

In general, each of the several cracking operations may be carried out as described in application Serial Number 198,621, mentioned above, except as to the handling of high boiling constituents condensed from the hot oil products discharged from the heating operations.

As illustrated, the digesting drums there described may be omitted and the hot oil products from the heating conduits may be discharged directly into the scrubbing towers. The heating furnaces may be arranged and operated, in general, as described in this mentioned application. The scrubbing towers may be arranged and operated, for example, as described in an application filed March 7th, 1929, Serial Number 345,199, by E. C. Herthel. The vapors

escaping from the fractionating towers may be handled, for example, as described in applications Serial Numbers 198,621, or 345,199, mentioned above, or in an application filed February 29th, 1928, Serial Number 257,958, by E. C. Herthel.

Fractionating towers 4a, 4b and 4c may be controlled by means of either or both of the groups of reflux condensers 25a, 25b and 25c, through which raw oil may be circulated as a cooling medium, and reflux condensers 26a, 26b and 26c, through which some extraneous cooling medium such as water may be circulated, or by means of the direct introduction of raw oil through connections 27a, 27b and 27c, or by means of such introduction of raw oil supplemented by the operation of one or more of the groups of reflux condensers just mentioned. Scrubbing towers 3a, 3b and 3c may be controlled by means of the reflux condensers 28a, 28b and 28c respectively, or by the direct introduction of raw oil through connections 29a, 29b and 29c respectively, or by means of such introduction of raw oil supplemented by the operation of the reflux condensers 28a, 28b and 28c.

In the production of motor fuel gasoline, for example, in apparatus such as that illustrated, the heating furnace 2a may be controlled so that the hot oil products are discharged from the heating conduit 1a at a temperature in the neighborhood of 1070-1090° F., the heating furnace 2b so that the hot oil products are discharged from the heating conduit 1b at a temperature in the neighborhood of 1110-1130° F., and the heating furnace 2c so that the hot oil products are discharged from the heating conduit 1c at a temperature in the neighborhood of 1150-1170° F., and the fractionating towers 4a, 4b and 4c may be controlled so that the temperature of the vapors escaping through connections 14a, 14b and 14c respectively approximates 400-500° F.

In carrying out the invention in the apparatus illustrated, the condensates separated in the successive fractionating towers 4a, 4b and 4c may be of the same general boiling range or may include, successively, increasing proportions of relatively lower boiling constituents. These condensates are, however, heated to successively higher cracking temperatures; the condensate from the fractionating tower 4a is heated to a higher temperature in the heating conduit 1b than is the raw oil in the heating conduit 1a, and the condensate from the fractionating tower 4b, or the mixture of condensates from the fractionating towers 4b and 4c, is heated to a higher temperature in the heating conduit 1c than is the condensate from the fractionating tower 4a in heating conduit 1b.

It is only to the heating conduit 1c that any high boiling constituents condensed from the hot oil products discharged from the heating conduit are returned, but it is also in the heating conduit 1c that the most severe cracking conditions are maintained. It will be appreciated that the ratio between the proportion of condensate returned to the heating conduit 1c from the fractionating tower 4c and the proportion of this condensate discharged from the fractionating tower 4c without return to the heating conduit 1c may vary widely, but in every case at least a part of all constituents condensed from the hot oil products discharged from the heating conduit 1c, following the separation of tar, is discharged without return to the heating conduit 1c. In general, a greater

total production of the desired product is accomplished by returning twenty per cent., for example, of this condensate to the heating conduit than by returning eighty per cent., for example, although

5 a higher proportionate yield of the desired product on the stock treated may be accomplished by returning the higher percentage to the heating conduit. As the ratio is reached at which high boiling refractory constituents begin to accumulate 5
10 within the operation, however, even the proportionate yield of the desired product usually fails to show any material increase. In this aspect, the invention makes it possible to attain the optimum operating balance between stock economy and operating economy.

15 In the first two steps of the improved operation of this invention, any accumulation of high boiling refractory constituents within the operation is avoided by avoiding any cyclic circulation of 20 such high boiling constituents through the heating operations, high boiling constituents condensed from the hot oil products discharged from the heating operations instead being separately subjected to more severe cracking conditions with 25 respect to which they are relatively less refractory. In the third step of the improved operation of the invention, any accumulation of high boiling refractory constituents within the operation is avoided by discharging, without return to the heating 30 operation, at least a part of all high boiling constituents condensed from the hot oil products discharged from the heating operation.

35 In one aspect, this last mentioned feature of the operation of the invention is itself an improved cracking operation. By discharging part of all high boiling constituents condensed from the hot oil products discharged from the heating operation, without return to the heating operation, while returning to the heating operation another 40 part of such condensed high boiling constituents, after separation of tar, any continuing accumulation of high boiling refractory constituents within the operation is avoided at the same time that a part of the stocks produced in the operation, heavier or higher boiling than the desired 45 product and freed from tar produced in the operation, is resubjected to severe cracking conditions with the recovery of additional quantities of the desired product.

50 I claim:

1. In cracking operations in which a higher boiling hydrocarbon oil is heated to a high cracking temperature in the vapor phase, the improvement which comprises heating a stream of raw 55 oil to a high cracking temperature in the vapor phase and subjecting the hot oil products of this heating operation to a scrubbing operation for the separation of tar, separately supplying liquid oil to and withdrawing tar from the scrubbing 60 operation, subjecting the vapors escaping from the scrubbing operation to a fractionating operation for the condensation of constituents higher boiling than suitable as components of the desired product and discharging condensate therefrom, 65 without returning any of this condensate to said heating operation, separately heating a stream of this condensate to a higher cracking temperature in the vapor phase and subjecting the hot oil products of this separate 70 heating operation to a second scrubbing operation for the separation of tar, separately supplying liquid oil to and withdrawing tar from the second scrubbing operation, subjecting the vapors escaping from the second 75 scrubbing operation to a fractionating operation

constituents higher boiling than suitable as components of the desired product and discharging condensate therefrom without returning any of this condensate to either of said heating operations, and preventing return to either of said heating operations of tar withdrawn from either of said scrubbing operations.

2. In cracking operations in which a higher boiling hydrocarbon oil is heated to a high cracking temperature in the vapor phase, the improvement which comprises heating a stream of raw oil to a high cracking temperature in the vapor phase and subjecting the hot oil products of this heating operation to a scrubbing operation for the separation of tar, separately supplying liquid oil to and withdrawing tar from the scrubbing operation, 10 subjecting the vapors escaping from the scrubbing operation to a fractionating operation for the condensation of constituents higher boiling than suitable as components of the desired product and discharging condensate therefrom without returning any of this condensate to said heating operation, separately heating a stream of this condensate to a higher cracking 15 temperature in the vapor phase and subjecting the hot oil products of this separate heating operation to a second scrubbing operation for the separation of tar, separately supplying liquid oil to and withdrawing tar from said second scrubbing operation, subjecting the vapors escaping from the second scrubbing operation to a fractionating operation for the condensation of constituents higher boiling than suitable as components of the desired product and discharging condensate therefrom without returning any of this condensate to either of said heating operations, 20 separately heating a stream of this condensate to a still higher cracking temperature in the vapor phase and subjecting the hot oil products of this further separate heating operation to a third scrubbing operation for the separation of tar, separately supplying liquid oil to and withdrawing tar from said third scrubbing operation, and subjecting the vapors escaping from the third scrubbing operation to a fractionating operation for the condensation of constituents higher boiling than suitable as components of the desired product and discharging condensate therefrom, 25 and preventing return to any of said heating operations of tar withdrawn from any of said scrubbing operations.

3. In cracking operations in which a higher boiling hydrocarbon oil is heated to a high cracking temperature in the vapor phase, the improvement which comprises heating a stream of oil to a high cracking temperature in the vapor phase and subjecting the hot oil products of this heating operation to a scrubbing operation for the separation of tar, separately supplying liquid oil to and withdrawing tar from the scrubbing operation, subjecting the vapors escaping from the scrubbing operation to a fractionating operation for the condensation of constituents higher boiling than suitable as components of the desired product and discharging condensate therefrom without returning any of this condensate to said heating operation, separately heating a stream of this condensate to a higher cracking temperature in the vapor phase and subjecting the hot oil products of this separate heating operation to a second scrubbing operation for the separation of tar, separately supplying liquid oil to and withdrawing tar from the second scrubbing operation, subjecting the vapors escaping from the second scrubbing operation to a fractionating operation for the condensation of constituents higher boiling than suitable as components of the desired product and discharging condensate therefrom without returning any of this condensate to said heating operation, separately heating a stream of this condensate to a still higher cracking temperature in the vapor phase and subjecting the hot oil products of this further separate heating operation to a third scrubbing operation for the separation of tar, separately supplying liquid oil to and withdrawing tar from said third scrubbing operation, and subjecting the vapors escaping from the third scrubbing operation to a fractionating operation for the condensation of constituents higher boiling than suitable as components of the desired product and discharging condensate therefrom, and preventing return to any of said heating operations of tar withdrawn from any of said scrubbing operations.

4. In cracking operations in which a higher boiling hydrocarbon oil is heated to a high cracking temperature in the vapor phase, the improvement which comprises heating a stream of oil to a high cracking temperature in the vapor phase and subjecting the hot oil products of this heating operation to a scrubbing operation for the separation of tar, separately supplying liquid oil to and withdrawing tar from the scrubbing operation, subjecting the vapors escaping from the scrubbing operation to a fractionating operation for the condensation of constituents higher boiling than suitable as components of the desired product and discharging condensate therefrom without returning any of this condensate to said heating operation, separately heating a stream of this condensate to a higher cracking temperature in the vapor phase and subjecting the hot oil products of this separate heating operation to a second scrubbing operation for the separation of tar, separately supplying liquid oil to and withdrawing tar from the second scrubbing operation, subjecting the vapors escaping from the second scrubbing operation to a fractionating operation for the condensation of constituents higher boiling than suitable as components of the desired product and discharging condensate therefrom without returning any of this condensate to said heating operation, separately heating a stream of this condensate to a still higher cracking temperature in the vapor phase and subjecting the hot oil products of this further separate heating operation to a third scrubbing operation for the separation of tar, separately supplying liquid oil to and withdrawing tar from said third scrubbing operation, and subjecting the vapors escaping from the third scrubbing operation to a fractionating operation for the condensation of constituents higher boiling than suitable as components of the desired product and discharging condensate therefrom without returning any of this condensate to either of said heating operations, separately heating a stream of this condensate to a still higher cracking temperature in the vapor phase and subjecting the hot oil products of this further separate heating operation to a fourth scrubbing operation for the separation of tar, separately supplying liquid oil to and withdrawing tar from said fourth scrubbing operation, and subjecting the vapors escaping from the fourth scrubbing operation to a fractionating operation for the condensation of constituents higher boiling than suitable as components of the desired product and discharging condensate therefrom without returning any of this condensate to either of said heating operations, and preventing return to any of said heating operations of tar withdrawn from any of said scrubbing operations.

for the condensation of constituents higher boiling than suitable as components of the desired product, dividing this condensate into two parts of the same composition and returning one part of this condensate to the said separate heating operation and discharging the other part of this condensate without returning it to either of said

heating operations whereby continuing accumulation of high boiling refractory constituents within the operation is avoided, and preventing return to either of said heating operations of tar withdrawn from either of said scrubbing operations.

WILLIS S. GULLETTE.
